UNITED STATES PATENT OFFICE.

DANIEL M. WATTERS, OF LOS ANGELES, CALIFORNIA, ASSIGNOR TO KILLEFER MANUFACTURING COMPANY, OF LOS ANGELES, CALIFORNIA, A CORPORATION OF CALIFORNIA.

ROAD TOOL.

Original application filed February 16, 1922, Serial No. 537,111. Divided and this application filed May 4, 1926. Serial No. 106,660.

This invention relates to a road tool of the character employed in the so called scarifying of roads provided with surfaces treated with oil, asphaltum or other substance that 5 can be cut, and is a division of my patent application, Serial No. 537,111, filed February 16, 1922.

An object of the invention is to provide a tool of this description in which the cutting discs can be manually raised and lowered very quickly so as to avoid manholes, rails and other obstacles encountered in road building and repairing.

In order to properly scarify a road surface, that is to cut off the ridges of the surface so as to make said surface more nearly smooth, it is necessary to make frequent small adjustments of the discs relative to the road surface so as to more or less follow the surface contour, as the road may be crowned or there may be comparatively large uneven surfaces which it is not the function of the scarifier to remove. It is also essential, for the reasons stated above, that it be 20 possible to adjust the discs relative to the road surface by relatively great movements quickly executed.

A further object of this invention is to meet the conditions noted above.

30 The accompanying drawings illustrate the invention:

Fig. 1 is a plan view of a road tool constructed in accordance with the provisions of this invention.

35 Fig. 2 is a side elevation of Fig. 1. The parts are shown in solid lines in the positions they occupy when the frame is lowered relative to the wheels, and broken lines indicate the positions of the parts when the frame 40 and its suspended discs are in raised position relative to the wheels.

Fig. 3 is an enlarged fragmental elevation mainly in section on line indicated by 3-3, Fig. 1.

45 Fig. 4 is an enlarged broken elevation, mainly in section on the line indicated by 4-4, Fig. 1.

50 Fig. 5 is an enlarged broken elevation, partly in section, from the line indicated by 5-5, Fig. 1.

The frame of the implement is indicated at 8 and said frame carries hangers 9 provided with bearings 10 for the shafts 11, on which discs 12 are mounted. The discs 12

are shown in four series, in this instance, 55 there being one series on each shaft. The discs of the series on opposite sides of the frame are arranged at an angle to one another as is customary in this type of road tool. At its forward end the frame 8 is provided with forwardly projecting arms 13 positioned above the level of the frame 8 and connected therewith by standards 14. The arms are mounted cantileverwise on the standards. To the forward ends of the members 13 is secured mechanism 15 for raising and lowering the forward end of the frame 8. The mechanism 15 will not be described in detail herein as it is the subject of the co-pending patent application hereinbefore referred to.

A yoke 36 is riveted at 37 to the members 13 and pivoted to the yoke at 38 is a draft tongue 39 whereby the road tool is drawn over the surface which is being operated 75 upon.

All of the frame members 42 are extended rearwardly and are provided with bearings 43 for crank axles 44, there being two bearings for each axle and two axles, one for 80 each side of the machine. Mounted on each pair of the members 42 somewhat forwardly of the bearings 43 is a post comprising plates 45, 451. The upper ends of the plates 45 constitute bearings 46 for the trunnions 85 47 of a trunnion nut 48. The trunnion nut 48 is engaged by a screw provided with two sets of screw-threads 49, 50 respectively. The screw threads 49 are the reverse of the screw threads 50. The upper end of the 90 screw is provided with a hand wheel 51 whereby the screw is turned.

The screw-threads 50 engage a second trunnion nut 52 having its trunnions 53 pivotally supporting one end of a pair of arms 55 which are secured by a V-shaped bracket 56 to the crank 57 of one of the crank axles. Each of the crank axles is provided with a ground wheel 58, and the rear end of the frame 10 is thus independently and adjustably suspended at opposite sides of the longitudinal center line of the machine. This together with the mechanism described above for adjustably supporting the forward end of the frame constitute a three point 100 suspension for the frame. The mechanism described for operating the crank 57 is provided for each of the cranks, that for op-

erating one being a duplicate of the other and, therefore, but one has been described. The arms 55 and crank arm 57 together constitute a lever of which the fulcrum is the hub of the wheel 58.

The operation of the tool described above is as follows:

Assuming that power is applied to the tongue 39 to draw the tool over the surface 10 of a road that is to be repaired, the hand wheels 20, 51, will be operated to lower the frame relative to the ground wheels 34, 58 so that the discs 12 will cut into the surface of the ridges in the road and thus level off 15 said ridges. While it is necessary to adjust the elevation of both ends of the frame 10 at intervals to produce the desired cutting of the road surface, shifting of the front end need not be so speedily effected as the rear 20 end. By raising and lowering the rear end of the frame, not only will the rearmost discs be raised and lowered, but the foremost discs will likewise be raised and lowered, though by a lesser distance than the rear 25 end. Assuming that the hand wheels 20, 51, have been adjusted to make the desired cut into the ridges or uneven places of the road, and that because of the approach of the machine toward a man-hole it is necessary to 30 raise the discs above the surface of the road, the operator will turn both hand wheels 51 to the right. The screw threads 49 being left hand, the screws will rise relative to the frame so as to swing the arms 55 and cranks 25 57 upwardly to raise the frame. Turning of the hand wheels 51 also causes the trunnion nuts 52 to travel upwardly on the screws, because the screw-threads 50 engaged by them are right hand. This of 40 course produces more rapid swinging upwardly of the arms 55 and cranks 57 to effect the raising of the frame. As soon as the man-hole has been passed, the hand wheels 51 will be turned to the left to effect lowering 45 of the frame so as to swing the discs 12 into cutting relation with the surface of the road.

The operator, by carefully observing the 50 depth of cut made by the forward series of discs, can accurately operate either or both of the hand wheels 51 to make a deeper cut with the rear series of discs in that portion of the ridge which has just passed the forward series of discs, so as to reduce the elevation of the ridges by a still greater amount.

These tools are of necessity relatively massive in construction and it is clear, therefore, that the frame elevating mechanisms should

operate easily and quickly to avoid the imposing of excessive strain upon the operators, since frequent raising of the discs is necessary to clear road obstructions such as manholes and because of working on comparatively short stretches of road and also 65 in cross leveling for adjusting to road inequalities.

Because of the provision of the members 13 and standards 14, the front axle can be turned to position at a right angle to the longitudinal axis of the machine, thus permitting the machine to be turned in a short radius and consequently not requiring that the discs be raised ten or twelve inches as would be necessary if a short turn could not 75 be made. This is important since the machines operate about three-quarters of the time on runs of but one or two blocks before turning.

It will be understood that a machine of 80 this description is subjected to considerable vibration when in service. By provision of the raising and lowering mechanism described, the vibrations do not destroy the adjustment as has been experienced with the 85 use of prior constructed lifting jacks designed for speedy raising and lowering of the discs.

I claim:

1. An implement of the character described comprising a frame, posts mounted on the frame and each provided with a trunnion nut, screws having upper and lower series of screw threads of reverse construction, said upper screw threads engaging the 90 trunnion nuts, nuts engaging the lower screw threads, means to turn the screws, wheels shiftably connected with the frame, and means operable by movement of the last mentioned nuts along the screws to elevate 95 the frame relative to said wheels.

2. An implement of the character described comprising a frame, an axle connected with the frame, posts mounted on the frame and each provided with a trunnion nut, screws provided respectively with series of threads engaging the nuts and provided respectively with other series of threads of reverse construction to the first mentioned series, nuts engaging said other series of threads, means to turn the screws, wheels shiftably connected with the frame and means operable by movement of the last mentioned nuts along the screws to elevate 110 the frame relative to said wheels.

Signed at Los Angeles, Calif., this 21 day of April, 1926.

DANIEL M. WATTERS.
